RUG MAKING IMPLEMENT

Lena Wullweber, Virgil, S. Dak.

Application November 27, 1935, Serial No. 51,903

1 Claim. (Cl. 112—9)

The invention relates to a rug making implement in the form of an attachment for domestic sewing machines for the manufacture of ornamental fabrics, such as, for example, pile rugs.

5 The primary object of the invention is the provision of an attachment of this character, wherein in the same is susceptible of use with a domestic sewing machine so that coiled strip material may be sewed to a backing and these coils severed uniformly at opposite sides of a run of tacking to the backing so that the severed coils will effect a pile surface and the tufts will be uniformly created throughout the manufactured fabric with twice the ease and speed of other 10 similar devices on the market.

Another object of the invention is the provision of an attachment of this character, wherein the construction thereof is novel in form so that the cutting blades are susceptible of being constructed in an upright position and set in one 20 fourth of an inch from the outer edge of the prongs to make a more even pile. The blades being held in a pair at one end of the guide and at opposite sides of a passageway for the needle of 25 the ordinary sewing machine tacks by stitching the coiled fabric to a backing and in this manner an attractive and efficient rug can be produced.

A further object of the invention is the provision of an attachment of this character, which 30 is simple in construction, light in weight, flexible for rewinding, thoroughly reliable and efficient in its operation, readily and easily handled, convenient for use with the domestic sewing machine, strong, durable, and inexpensive to manufacture.

With these and other objects in view, the invention consists in the features of construction, combination and arrangement of parts as will be 40 hereinafter more fully described, illustrated in the accompanying drawing, which discloses the preferred embodiment of the invention and pointed out in the claims hereunto appended.

In the accompanying drawing:

45 Figure 1 is a perspective view of the device constructed in accordance with the invention shown in position for the tacking of the coiled fabric to a backing with the coils in position to be severed by the device.

50 Figure 2 is a sectional view on the line 2—2 of Figure 1 looking in the direction of the arrows.

Figure 3 is a sectional view on the line 3—3 of

Figure 2 looking in the direction of the arrows.

55 Figure 4 is a sectional view on the line 4—4 of Figure 3 looking in the direction of the arrows.

Figure 5 is a sectional view on the line 5—5 of Figure 3 looking in the direction of the arrows.

Figure 6 is a fragmentary transverse sectional view through a small portion of a completed rug 5 as created by the device.

Similar reference characters indicate corresponding parts throughout the several views in the drawing.

Referring to the drawing in detail, the attachment comprises an elongated flexible flat plate 10 which must be of uniform width for a major portion of the length thereof and is formed with a slot 11 centrally located and extending for a greater portion of the length of said plate and 15 provides the closed end 12 and the mouth or open end 13, respectively, the corners of the mouth end being rounded at 14. This plate 10 must be made from rather flexible sheet steel having the required rigidity and strength for 20 longevity. Cut and bent from the blank from which the plate 10 is cut or formed at an open end and at opposite side edges are blade housings 15, these being arranged at right angles to the plane of the top face of the plate 10 and rise 25 therfrom.

The housings 15 at their inner ends have inwardly tapered openings 16, the wider ends of which open through the said inner ends of the housings 15 and exposed through these openings 30 16 are cutting blades 17, they having beveled cutting edges 18 for shear cutting of coiled strip material 19 such as is trained about the plate 10. The housings 15 at the openings 16 are formed with nibs 20 which constitute stops for the blades 35 17 to prevent the possibility of these working out of the housings 15 when confined therein as is clearly shown in Figures 1 and 3 of the drawing, there being nibs in the lower inner wall of the blade housings with corresponding slots in the 40 plate 10 for holding the housings firm when in operation. The coiled material 19 is wrapped about the plate 10 and beneath this plate is arranged a fabric backing piece 21 so that the coils 19 prior to severance thereof can be tacked by 45 stitches 22 created in the operation of a domestic sewing machine. The stitches in the line of tacking thereof follow the slot 11 in the plate 10 as the needle is guided through the slot when the sewing machine is being operated. The end of 50 the plate 10 remote from the housing 15 is formed with a finger engaging lip or tongue 23 which is upturned from this plate and is serviceable for convenient handling of the plate 10 when the same is to be drawn through the coils 19 after 55

being stitched to the backing piece 21 for the severing of the coils one fourth of an inch in from the fold ends 24 of such coils so that an even pile fabric as is shown in Figure 6 will be created.

- 5 The plate 10 is adapted to be disposed between the sewing bed of a sewing machine and the foot piece so as to have the needle travel through the slot 11 for the stitching of the coils of material 19 as wrapped about the plate 10 to the backing piece 21, this piece 21 being moved beneath the foot piece by hand. When the coils 19 have been tacked to the piece 21 the plate is pulled through the coils which slides the same over the blades 17 for the severing of the coils one fourth of an 10 inch in from the folds 24 thereof with the result that an even pile fabric is produced.

15 The housings 15 at the outer ends thereof are closed by a tiny cut in folded over metal flap 25 and by the openings of this flap, which should spring into position, the blade 17 within the housing 15 can be removed for the placing of a new 20 blade therein.

It is desired to inset the housings 15 one fourth 25 of an inch from the opposite outer sides or longer edges of the plate 10 to bring the blades 17 into shearing position one fourth of an inch in from the folds 24 of the coils 19 of material about the

plate 10 of the attachment. The plate 10 has the slots 26 for accommodating lugs or tongues 27 provided at the lower edge of each housing so as to fasten the latter in vertical position upon the plate 10 at the inner side of said housing, such 5 housing is cut and folded from the plate, the outer side or wall of the housing being integral with this plate.

While there has been illustrated and described the preferred embodiment of the attachment the 10 same is capable of variation and modification without departing from the spirit of the invention and as comes within the scope of the claim hereunto appended.

What is claimed is:

An implement of the character described comprising a flat elongated centrally slotted plate having the slot opening through one end and a hand grip at the other end, housings rising from the plate on opposite sides and at the open end 20 of the slot thereof and having inwardly tapered openings in their inner ends, and beveled cutting blades fitted within said housings, the said housings being inset from the opposite side edges of said plate and rising vertically at substantially 25 right angles to the top face of the plate.

LENA WULLWEBER.
